1 Claim. (Cl. 334—47)

ABSTRACT OF THE DISCLOSURE

A frequency determining circuit incorporated in a frequency shift oscillator to furnish good stability and elimination of jitter. The circuit consists essentially of two inductances, L_1 and L_2 , connected in parallel; two capacitors, C_1 and C_2 , series-connected; and a switch S which performs change-over actions in such a manner that it disconnects the short circuiting of C_2 when L_2 is to be connected and short circuits C_2 when L_2 is disconnected. The two change-over actions are carried out in accordance with a direct current pulse.

This invention relates to FS (frequency shift) modulation systems of carrier telegraphy and more particularly to a new frequency determining circuit in a frequency shift oscillator.

The nature and details of the invention will now be described with respect to a preferred embodiment of the invention and conventional circuits corresponding to this invention in connection with the accompanying drawings, in which:

FIG. 1 and FIG. 2 are circuit diagrams of two different examples of conventional frequency determining circuits;

FIG. 3 is the equivalent circuit diagram of the embodiment of the frequency determining circuit according to this invention;

FIG. 4 is a circuit diagram for explanation of one example of a jitter-free circuit; and

FIGS. 5a, b, c, d are waveform diagrams for a description of jitter of the FS oscillator.

In an FS (frequency shift) modulation system of carrier telegraphy, the frequency of the carrier is changed over between f_1 and f_2 in response to the polarity or the on-off state of the D-C pulse according to the information to be transmitted.

The frequency determining circuit in the conventional FS oscillator which is widely used for this purpose is substantially a resonance circuit such as shown in FIGS. 1 and 2, in which some part of reactance is opened or closed by a switch S in accordance with the D-C input pulse such as for example shown in FIG. 5a. This opening or closing of the reactance causes a discontinuity of phase angle or jitter at the instant when the frequency is converted from f_1 to f_2 or vice versa. When this wave having jitter arrives at a discriminator on the receiver side of the type to obtain D-C output proportional to the time differentiation of the phase angle, the jitter causes irregular distortion in the received D-C pulse. To solve this problem, a proposal has been made in The Bell System Technical Journal, November 1962, in which the current voltage ratio

$$\frac{i(t)}{V(t)}$$

and the characteristic impedance

$$\sqrt{\frac{L}{C}}$$

of the tank circuit is recommended to be kept unchanged during the transfer of the frequency from one to the

2

other, and to realize this condition, the use of two active reactance oscillators connected in parallel is recommended for transferring of two frequencies. But owing to the active circuit elements, the frequency stability for the temperature variation is inferior to that of the conventional oscillators, and the circuit is too complicated for practical use.

This invention contemplates the provision of a simple and practical FS oscillator which, without departing too much from its ordinary composition, the conventional arrangement, has good frequency stability and can almost eliminate jitter by utilizing a suitable frequency determining circuit.

An example of the cause of jitter in the conventional circuits is indicated in FIG. 1, where, at the instant of closure of the switch S, the electrostatic charge stored in the capacitor C_2 is discharged, losing voltage, but the current value in this tank circuit cannot be varied instantaneously because of the inductance L_1 , and the value of

$$\frac{i(t)}{V(t)}$$

is changed before and after the switch operation. Since at the same time the characteristic impedance changes from

$$\sqrt{\frac{L_1(C_1+C_2)}{C_1C_2}} \text{ to } \sqrt{\frac{L_1}{C_1}}$$

a high jitter occurs. Then when the switch S is opened again the current and voltage are kept constant, but since the characteristic impedance also changes, jitter is caused. In the case of FIG. 2, these states occur in an exactly opposite manner, and jitter occurs also at the opening and closing of the switch S.

To improve this defect, the FS oscillator according to this invention is composed and arranged as indicated in FIG. 3. Here, the frequency determining circuit comprises two inductances L_1 and L_2 connected in parallel, two capacitors C_1 and C_2 connected in series, and a switch S which, when it is turned to position 1, short circuits the capacitor C_2 and at the same time opens inductance L_2 , and when it is turned to position 2, connects the inductance L_2 and disconnects the short circuiting of the capacitor C_2 , these changeover actions of the switch S being performed instantaneously. If it is supposed that the switch S is placed in the position 1 when the D-C pulses is in the space state, then when the D-C pulse changes from space to mark, the switch S will be turned to position 2. During the above operation, the inductance L_2 which at first has no current is connected in parallel to the tank circuit, and the capacitor C_2 which at first had no electrostatic charge is connected in series to the tank circuit. Accordingly, no disturbance of the current and the voltage at points P_1 and P_2 is caused, and hence the values of the current and the voltage are kept constant continuously before and after the operation of the switch S. Moreover, by selecting L_2 and C_2 to be suitable values respectively, the characteristic impedance

$$\sqrt{\frac{L_1}{C_1}}$$

of the tank circuit just before the switch operation can be readily made equal to the characteristic impedance

$$\sqrt{\frac{L_1L_2(C_1+C_2)}{(L_1+L_2)C_1C_2}}$$

just after the switch operation. Therefore, no jitter occurs in this circuit with respect to change from space to mark.

Next, the case when the D-C pulse is shifted from mark to space will be considered. The switch S is changed from position 2 to position 1. In this case the characteristic impedance is not changed, being kept at a constant value similarly as in the above case of change from space to

mark. However, the electrostatic charge stored in the capacitor C_2 is discharged at the instant when the capacitor is short circuited, whereby the voltage $V(t)$ decreases. However, the current which has been flowing at the same time through the inductance L_2 is abruptly released, causing the current $i(t)$ to decrease. Consequently, the ratio

$$\frac{i(t)}{V(t)}$$

at the points P_1 and P_2 is kept at a constant value before 10 and after the change-over, theoretically causing no jitter due to phase angle discontinuity.

As hereinabove described, in the FS oscillator according to this invention, far less jitter occurs due to only the amplitude discontinuity in comparison with the conventional FS oscillator, the frequency being determined almost solely by the passive elements such as L_1 , L_2 , C_1 and C_2 . Therefore the frequency stability with respect to 20 temperature variation and characteristic deviations of the circuit elements is superior to that of the reactance type oscillator.

In the above description, the switch is described as a knife switch for the sake of simplicity, but it will be obvious that the switch can be materialized by any other type such as a diode switch. Furthermore, the composition and arrangement of the circuit also can be modified within the scope of this invention, for instance, by using one tapped

inductance instead of the two inductances, so long as this component can be indicated by the same electrically equivalent circuit as that shown in FIG. 3.

Accordingly, it should be understood that the foregoing disclosure relates to only a preferred embodiment of the invention and that it is intended to cover all changes and modifications of the example of the invention herein chosen for the purposes of the disclosure, which do not constitute departures from the spirit and scope of the invention as set forth in the appended claim.

What we claim is:

1. A frequency determining circuit of a frequency shift oscillator, said circuit being equivalent at least electrically to a circuit comprising a first circuit having an inductance 15 L_1 connected in parallel to two series-connected capacitors C_1 and C_2 and switching means to accomplish, in response to D-C signal pulses, the two change-over switching operations of opening a short-circuit connection of the capacitor C_2 when another inductance L_2 is connected in parallel to said first circuit and of disconnecting the inductance L_2 when the capacitor C_2 is short circuited.
